UNITED STATES PATENT OFFICE.

WILLIAM A. RICHARDSON, OF CHICAGO, ILLINOIS, ASSIGNOR OF ONE-HALF TO JOHN G. BARRETT AND ONE-HALF TO EDMOND M. KENNEALY, OF CHICAGO, ILLINOIS.

ELECTRIC LAMP.

1,033,347.

Specification of Letters Patent.

Patented July 23, 1912.

Application filed July 3, 1911. Serial No. 636,611.

To all whom it may concern:

Be it known that I, WILLIAM A. RICHARDSON, a citizen of the United States, and a resident of the city of Chicago, county of Cook, and State of Illinois, have invented 5 certain new and useful Improvements in Electric Lamps, of which the following is a specification.

My invention relates to improvements in 10 electric lamps.

At the present time where a plurality of electric lamps are connected in series in a circuit, when the filament in one of the lamps breaks or becomes otherwise disabled 15 considerable difficulty and inconvenience is experienced and considerable time is lost in endeavoring to ascertain which lamp is disabled, since, when the current is broken by one lamp, all of the lamps in the circuit will 20 be extinguished.

It is the object of this invention to produce a lamp in which will be provided means for cutting out the filament and so that in the event of the latter being broken 25 or disabled, the circuit through the lamp may be closed notwithstanding the disabled filament, thus providing means for readily ascertaining which lamp in the series is disabled; it being clear that by testing the successive lamps of the series by closing the short circuit therethrough by means of my improved mechanism, the lamps will remain 30 unlighted until the circuit through the defective lamp is closed, in which event all 35 of the lamps, with the exception of the defective one, will be lighted. Thus the defective lamp may be ascertained.

A further object is the production of mechanism as mentioned which will be of 40 durable and economical construction and efficient in operation.

Other objects will appear hereinafter.

With these objects in view my invention 45 consists in improvements in an electric lamp characterized as above mentioned and in certain details of construction and arrangement of parts hereinafter described and claimed.

My invention will be best understood by 50 reference to the accompanying drawing forming a part of this specification, and in which,

Figure 1 is a sectional side elevation of an 55 electric lamp and socket to which is applied mechanism embodying the preferred form of my invention, Fig. 2 is a slightly enlarged

transverse section taken on substantially line $x-x$ of Fig. 1, Fig. 3 is a sectional side elevation similar to Fig. 1 of an electric lamp and socket in which is arranged mechanism embodying a slightly modified form of 60 my invention, and Fig. 4 is a transverse section taken on substantially line $y-y$ of Fig. 3.

Referring now to the drawing I have illustrated an electric lamp and socket of conventional construction, the latter comprising a metallic casing 1 in the lower end of which is arranged the porcelain block or plug 2 within which is mounted the electric switch which is operable by the switch button 3 in the usual manner. Arranged in the upper end of the casing 1 is the screw threaded metallic member 4 which is secured rigidly to the member 2 and connected with the switch therein in the usual manner so 65 that said member 4 constitutes a terminal for engagement with the lamp. The second terminal of the socket is shown at 5 provided as usual centrally upon the upper side of the member 2. The members 2 and 4 are 70 shown insulated from the casing 1 as is ordinary by the insulation 6.

The lamp 7 is provided with the usual metallic screw threaded end 8 which is adapted for threading into the socket member 4, said member 8 constituting one of the terminals of the lamp for contact with the terminal 4 of the socket. The other terminal 9 of the lamp is provided centrally 75 at the inner end of the latter for contact under ordinary circumstances with the terminal 5 of the socket.

The construction thus far described is old and well known, no claim being here made thereto, the construction which forms the 80 subject matter of this invention being set forth in the following, such construction being designed for use in conjunction with any electric lamp of conventional construction, it being understood that no limitation 85 is made to its use in conjunction with the lamp and socket construction shown in the drawing.

Arranged upon the upper end of the 90 socket member 2 is a substantially U-shaped metallic spring member 10 which is secured in position at its lower end by the terminal member 5. The member 10 is so arranged 95 that when the lamp is threaded into the socket the upper end of the former will be 100 105 110

positioned for contact with the terminal 9 to complete the electrical connection between the socket and the lamp, the current passing as is known from the terminal 9 through the lamp filament thence through the terminal 8 of the lamp to the terminal 4 of the socket.

In the preferred form of my invention a resilient spring member 11 is provided, one end thereof being secured as by soldering to the socket member 4, the latter being cut away as at 11' to permit of free movement of the free end of said member 11. The latter is arranged coplanar with the member 10 and is adapted when the free end thereof is pressed inwardly to contact the member 10 in order to establish an electrical connection between the contacts 5 and 4 of the socket. Depression of the free end of the member 11 is effected through the medium of a button 12 which is slidably mounted in the adjacent side of the casing member 1. With this construction when it is desired to close the circuit between the terminals of the lamp socket it is only required to depress the button 12 until the free end of the member 11 contacts the member 10, said button being formed of a suitable non-conducting material such as fiber.

With the construction then as above set forth where a plurality of electric lamps are connected in series and where the filament of one of the lamps is broken as first mentioned the defective lamp may be readily and expeditiously located by simply depressing the buttons 12 of the successive lamps until all of the lamps, with the exception of the defective one, light up as first described; the provision of the construction set forth in the lamp providing means whereby the passage of the electrical current through the lamp may be short circuited in order to cut out the lamp proper.

In Figs. 3 and 4 wherein is illustrated the modified form of the invention the member 11 and button 12 are dispensed with and in lieu thereof the free end of the member 10 is provided with an extension 10' adapted when said free end of said member is de-

pressed to contact the base portion of the 50 socket member 4 and thus establish connection between the two socket terminals. Such depression of the free end of the member 10 is effected by simply turning the lamp 7 farther into its socket as is readily apparent 55 from Fig. 3. The latter construction is designed for employment in conjunction with electric lamps where the sockets are not exposed such as in electric illuminated sign construction.

The construction as set forth is durable and economical and is adapted to effectually serve the purpose for which the same is designed.

While I have illustrated and described 65 the preferred forms of construction for carrying my invention into effect, these are capable of variation and modification without departing from the spirit of the invention. I therefore do not wish to be limited 70 to the precise details of construction as set forth, but desire to avail myself of such variations and modifications as come within the scope of the appended claim.

Having described my invention what I 75 claim as new and desire to secure by Letters Patent is:

In a device of the character described, the combination with an electric lamp socket; and an electric lamp, said socket 80 having two terminals adapted for contact with the terminals of said lamp to complete a circuit through said lamp; resilient means interposed between two of the coöperating terminals of said socket and lamp adapted 85 normally to establish connection between said terminals and adapted to be depressed by said lamp upon turning of the latter in said socket to establish connection between the terminals of said socket to cut out said 90 lamp, substantially as described.

In testimony whereof I have signed my name to this specification in the presence of two subscribing witnesses.

WILLIAM A. RICHARDSON.
